UNITED STATES PATENT OFFICE.

HERBERT S. ATKINSON, OF EAST ORANGE, NEW JERSEY, ASSIGNOR TO THE HAYWARD COMPANY, OF NEW YORK, N. Y., A CORPORATION OF NEW YORK.

BUCKET.

Application filed January 31, 1925. Serial No. 5,951.

To all whom it may concern:

Be it known that I, HERBERT S. ATKINSON, a citizen of the United States, and residing in East Orange, in the county of Essex and 5 State of New Jersey, have invented certain new and useful Improvements in Buckets, of which the following is a specification.

This invention relates to new and useful improvements in buckets such as are commonly employed for loading, unloading, dredging, and similar work, and, more particularly, to improvements in the chain constructions covered by my former Patents 10 No. 889,170 of May 26, 1908, and No. 15 906,184 of December 8, 1908, respectively.

In the patents above referred to, the operating chain, consisting of a single portion and a duplex portion, is attached to the upper center shaft by the single portion of the 20 chain through a suspending bar, while the duplex portion is attached to the hub of the power wheel, the latter being slotted to receive the end links of the chain and longitudinally bored for a fastening pin.

25 In the use of these operating chains, the principal objections that developed were that the greatest stress, coming when the bucket was nearly closed, was thrown on the single portion of the chain, the last to wind over the hub in the closing operation, and that no 30 means was provided for allowing for inequalities in bearings or length of members. In the present invention I have overcome 35 these objections by a re-arrangement of chain, in which I attach the single portion of the chain by a simplified connection to the hub of the power wheel, while the duplex portion, now the last to wind over the hub in the closing operation and better 40 fitted to take the strain, is attached to the upper center shaft by a suspender strap or rod, through the interposition of an equalizer bar. The arrangement materially reduces and minimizes the wear on the parts 45 of the chain as well as the bucket elements, and permits a heavier construction of the upper or double section of the chain.

50 In the accompanying drawings, forming a part of this application,

55 Figure 1 is a side elevation of a bucket constructed in accordance with my invention, the scoops being shown in closed position in full lines and in open position in dotted lines;

Figure 2 is a front elevation of the same;

Figure 3 is an enlarged side elevation, with parts in section and parts broken away, showing in detail the chain construction and support;

Figure 4 is a section therethrough taken 60 at right angles to Figure 3;

Figure 5 is an elevation of one of the power chains; and

Figure 6 is a detail section as seen on the line 6—6 of Figure 3. 65

In referring to the drawings, similar reference characters designate corresponding parts throughout the several views.

1 and 2 indicate, respectively, the bucket sections of a "clam-shell" bucket, the arms 70 3 and 4 of which are pivotally connected to a transverse shaft 5. The outer ends of the bucket sections have pivotally connected thereto, as shown at 6, the outer ends of pairs of side connecting bars 7, the latter being pivotally connected at their upper 75 ends to the upper center shaft 8. Adjacent to the point where it is pivoted to the shaft, each of the bucket sections is provided with a diagonal brace as at 9.

80 Mounted upon the shaft 5 for rotation thereon is a sleeve or drum 10, to the center of which is secured or formed a power wheel 11, the periphery of the latter being grooved to receive therein an operating cable 12, by 85 means of which the bucket sections are manipulated. This cable passes through an opening 13 in the periphery of the power wheel 11 and is secured permanently to the latter at a point designated by the numeral 90 14, as clearly shown in Figure 3 of the drawings, and it also passes over a guide pulley 17 supported by arms 18 projecting laterally from the head 19, which is also provided with depending leg portions 20 secured to one pair of the side connecting bars 7, as shown in Figures 1 and 2 of the drawings. 95

100 Mounted on the shaft 5 and extending on each side of the power wheel 11, as shown in Figure 1, is the rope guard 15, each arm of which is provided with a shoe 16 for securing the rope within the groove of the power wheel.

105 A holding line 21 is connected with a pin 22 mounted transversely on the upper end of the head 19.

110 To the foregoing I make no claim of novelty, as the elements are all old and their mode of operation is well known. I will now proceed to describe the arrangement of

the power chain which constitutes my present invention.

The drum or hub 10 is provided, on each side of the power wheel 11, with a raised portion or nub 10', which has a suitable recess or slot 10'', in which the lower extremity of the single portion of the chain is sunk and secured by the transverse pin 26 inserted in a suitable aperture through said nub 10'.
10 The upper ends of the duplex portion of the chain are pivotally connected to the equalizer bars 24, which, in turn, are pivotally connected to suspension straps 23, the latter being pivotally supported at their upper ends to the upper center shaft 8.

The chain referred to, as it appears detached from the bucket is shown in Figure 5 of the drawings, the double section being indicated at 25 and the single section at 25'.
20 It is so constructed that in the closing of the bucket the single section will wrap completely around the drum without overlapping, and, as the drum continues to rotate in the action of closing the bucket, the duplex section will wrap on each side of the single section of the chain without coming in contact with the latter until the bucket is closed.

In my Patent No. 906,184, of December 8, 30 1908, I have shown the same chain construction, but in said patent the duplex section of the chain connects with the drum, while the single portion connects with the upper suspension bars.

35 By the present arrangement, with the duplex portion of the chain the last to wind over the hub in the closing operation, the maximum strain, which occurs at the end of the closing movement, is now taken by the duplex or double portion of the chain, which, besides its additional element, may now be made of heavier construction.

Under the old arrangement the end links of the duplex portion of the chain were sunk 45 into the drum into suitable slots in the hub and secured therein by transverse pins. This arrangement materially affected the size of the parts. In the present arrangement I am able to use a raised portion or nub for the 50 end link of the single portion of the chain,

which expedient for obvious reasons would have been an impossibility for fastening the duplex ends of the chain.

Having thus described my invention, what I claim is:

55 1. The combination of a bucket formed of a plurality of sections, mechanism for operating said sections including a power wheel having a hub portion, and a chain for opening and closing the bucket sections comprising a single section and a plural section, the single section being secured to the hub of the power wheel and adapted to make a single turn about the same, and the members of the plural section being adapted to 60 make a single turn around said hub on either side of the single section.

2. A bucket comprising a plurality of sections, a pivot about which said sections move, a power shaft connecting said sections, a power wheel, and a chain for opening and closing the bucket sections comprising a single section and a plural section, the single section being secured to the power wheel and the plural section being suspended from said 75 pivot.

3. A bucket comprising a plurality of sections, a pivot about which said sections move, a power shaft connecting said sections, a power wheel, a chain for opening 80 and closing the said sections of the bucket comprising a single section and a plural section, the single section being secured to said power wheel and equalizing elements connected with said plural section and with the 85 aforesaid pivot.

4. A bucket comprising a plurality of sections, a pivot about which said sections move, a power shaft connecting said sections, a power wheel, chains for opening and 90 closing the bucket sections each comprising a single section and a plural section, the single section being secured to said power wheel, and equalizing elements suspended from the aforesaid pivot consisting of suspension 95 straps pivoted at their upper ends and cross-bars pivoted to the lower ends thereof and engaging the plural sections of said chains.

HERBERT S. ATKINSON.
